VENDING MACHINE

Harold D. Baum, Chicago, Ill.

Application April 4, 1952, Serial No. 280,612

15 Claims. (Cl. 221—84)

This invention relates to vending machines. It provides an automatic machine of this type which commands a particularly high degree of selling appeal, while involving simple and inexpensive construction and maintenance.

The new machine has a number of superposed shelves, each with a number of magazine channels, arranged side by side. The shelves and channels are so disposed that a variety of types of merchandise—usually one type per channel—can be displayed and automatically vended, and that it is possible at least for a great majority of types of merchandise to be fully displayed and efficiently manipulated without wrapping or packing; a feature which is desirable both from the standpoint of sales appeal and cost and which has not previously been achieved in workable vending machines for a plurality of types of merchandise.

The machine can be serviced rapidly and simply. Both reloading and maintenance operations can be performed by relatively unskilled personnel; pertinent complications of earlier machines of this class being avoided.

The display of goods for sale, in this new machine, resembles that in some of the self-service stores developed in recent years, as distinguished from the limited or lacking display of the chute type and other earlier types of vending machines.

These and other features of the new machine will be understood more fully upon a study of the detailed description of a preferred embodiment, which follows. In this description specific details will be explained; but it should be understood that such details are shown only for illustration and that the scope of the invention is indicated by the claims appended.

In the drawing:

Fig. 1 is a diagrammatic front view of a vending machine in accordance herewith. Figure 2 is a side view of the machine, with a side panel removed. Figures 3 and 4 are sections along lines 3—3 of Fig. 2 and 4—4 of Fig. 1 respectively.

Fig. 5 is a view on a larger scale, taken along lines 5—5, of Fig. 1. Figures 5A and 6 are views taken along the respective lines in Fig. 5. Fig. 7 is a bottom view of Fig. 5.

Fig. 8 is a view on approximately the same scale as in Fig. 5, taken along lines 8—8 of Fig. 1. Figs. 9, 10 are views taken along lines 9—9 and 10—10 in Figs. 8 and 9, respectively.

Figs. 11 and 12 are views taken along lines 11—11 and 12—12, respectively, in Fig. 8. Fig. 13 is a modification of Fig. 6.

Fig. 14 is a wiring diagram for the electrical system forming part of the machine.

In this machine there are vended a variety of types of merchandise, either packaged or not, having different outer dimensions, weight, hardness, etc. An item of one type is diagrammatically indicated by the circle M-1; it may consist for instance in a flat cylindrical container, displayed with a flat side facing the front. An item of

2

another type is similarly indicated by the square M-2; this may consist for instance in a deeper cylindrical container, displayed with part of the cylindrical side facing the front. Obviously, it is desirable to vend an endless variety of containers, bottles, boxes, articles, etc.; and while no more than two items M-1 and M-2 are specifically illustrated, the present machine has almost unlimited possibilities in this respect.

When the machine is loaded with merchandise it receives a number of items of each type M-1, M-2 etc., forming a row R-1, R-2 etc. These rows of merchandise items are supported on superposed shelves 10-A, 10-B etc. Each row extends from the back to the front of the machine, displaying mainly the front item. The vending mechanism is so arranged that the specific item of merchandise, vended in each successive, automatic vending operation, is identical with the item in full display; not only represented thereby. This feature, together with the variety of items on display, adds greatly to the sales appeal of the machine.

The basic principle of operation, in this machine, provides that the purchaser first selects the desired row R-1, R-2 etc. by operating a device such as a hand-wheel 11 to move a vertical row indicator and motor standard 12 to the proper position. He must then insert the proper coin or coins in a coin slot 13. Next he can press one of several superposed push-buttons 14-A, 14-B etc., corresponding in position and number to the shelf 10-A, 10-B selected. The so-selected item of merchandise is promptly discharged from its magazine row by a mechanism which responds to the dropping of the coin; this mechanism comprising linkage actuated by one of several superposed motors 15A, 15B etc. on the motor standard 12. The discharged merchandise item falls, in front of the purchaser, into a suitable trough 16 at the bottom of the machine, from which it is picked up manually.

In order to allow this simple form of a vending process, the shelves 10A, 10B etc. are combined into a rigid frame 17 (Fig. 5), inserted in a cabinet 18 which has in front a window 19, substantially as wide and high as is the set of shelves (Fig. 1). The display obtained in this manner is more direct than that connected with the usual vertical-chute vending machine. Further, this display is considerably more varied than the usual one of chute type machines and the like; the flat shelves can be loaded with a great variety of types of merchandise, without much regard for dimensions and proportions. The different types can rather be arranged according to price levels; for instance ten cent items on the lowest shelf; twenty-five cent items on the next; thirty-five cent items on the next; etc. This manner of display resembles that of successful self-service stores. The idea had occurred to me that a miniature store of this kind, with automatic vending provisions, should be particularly efficient in operation. I found this true, and found it further possible to make it economical in both manufacture and service; more so than any combination of chute type machines and the like. I also found it possible to avoid all difficulties arising from the storage or discharge of merchandise items of different size and shape. Such difficulties existed and were known for a long time.

I form each shelf 10A etc. with a series of magazine channels 20A, 20B etc.; generally using one channel for each row R-1, R-2 of merchandise, although specially wide items of merchandise may cover more than one channel. These channels, as best shown in Figs. 4 and 5, run the entire distance from the front to the back of the shelf. Thereby they allow the use, in each channel, of an endless conveyor band 21, with an operating run directly below the shelf, a parallel return run further

down, and with merchandise spacing and propelling lugs 22 on the band which extend upwardly from the operating run and through the channel and which, after discharge of the merchandise, turn with the band around a front conveyor roller 23 to form the return run of the band. The different portions 10A, 10B etc. of the merchandise supporting shelf, being separated by the channels 20A, 20B, are held together, in front, by a shaft 24 which also serves as a pivot for the front rollers 23, and in back by a similar shaft 25 for back rollers 26. This back shaft 25 can be structurally supplemented by a structural frame element 27 adjacent the rollers 26, since it is unnecessary to provide for any turning of lugs 22 at the back edge of the shelf; such lugs being required, and provided, only for the merchandise with which the machine is loaded, that is, on top of the shelves. Both shafts 24, 25 can be fairly sturdy and rigid. They do not have to turn; the rollers 23, 26 can be rotatably journaled thereon. Lateral shifting of such rollers is prevented by stop members 23A, Fig. 5A, 6. The available strength or thickness of these shafts, and diameter of the rollers is limited only by considerations of dimensions of merchandise to be vended, as will be explained.

In order to propel each conveyor band 21 by the proper distance in accordance with the dimensions of the merchandise in question, I provide, as best shown in Figs. 5 and 8, a pusher rod 28A, 28B etc. for each channel 20A, 20B etc., for actuation by the motor drive 15 and with a mechanism to engage and disengage the conveyor band 21 at the proper points. Each pusher rod is disposed below and parallel to the shelf, and slidably guided in bearings 29, 29, in a direction parallel with the respective channel. Each rod is closely surrounded by a compression spring 30, abutting against one of the fixed bearings 29 and pushing against a washer 31 secured to the movable rod, whereby the spring tends to move the rod backwards until it is stopped by impingement of a pin 32 adjustably secured to the rod, against a fixed object like one of the bearings 29 (see Fig. 12). By longitudinally adjusting the stop pins 32 of the different rods 28, these rods are caused to make strokes of different lengths, while being actuated by standardized motors 15 having identical stroke lengths.

The motion of each rod is transmitted to the respective conveyor by a clevis 33 at the front end of the rod; which clevis is adapted at the proper points to engage service lugs 34, extending downwards from the merchandise spacing lugs 22 on the operating run of the band 21. The band, including the lugs, is spaced laterally of the body of the pusher rod, but the clevis 33 on the rod is adapted to swing into a transverse position to engage the service lugs. For this purpose, as best shown in Figs. 7 and 12, the clevis 33 is swingably secured to the front end of the rod 28 by a pivot 35, and is loaded by a small torsion spring 36 to swing about this pivot into a position at right angles to the rod. In this position, further movement of the clevis is stopped by contact between a side surface on the clevis and the end surface of the rod. When thus positioned transversely of the rod, and longitudinally shifted with the rod by the motor, the clevis comes into contact with the nearest service lug 34 of the conveyor band 21, and shifts the same and thereby the corresponding merchandise item to the front of the machine.

The desirable extent of forward shifting is determined by the depth of the merchandise (measured in the direction of the channel 20). This dimension differs for the different types of merchandise, and therefore the desirable, useful stroke lengths of the different actuator rods 28A, 28B, etc. are desirably different. However, for simplicity of mechanical operation, uniform motor strokes are preferably used. Therefore I use uniform "total stroke lengths" for all actuator rods, but vary what may be called the "active stroke length" of each rod. This is achieved by the stop pins 32 and by installing, in connection with each rod, a guard 37 of suitable length,

extending parallel with and closely adjacent to the front end of the rod (Figs. 7 and 12). In its normal position, backwardly retracted by the spring 30, each rod has its clevis in close contact with the guard and consequently forced into longitudinal position and out of the path of the service lugs; thereby facilitating manual operation of the conveyor in reloading and servicing the machine. When actuated by the motor 15, each rod moves forward such a distance as is provided by its previous retracted position (controlled by the stop pin); and the clevis 33 moves into the path of the service lugs 34 at the exact point where it passes the end of the guard 37.

For instance, the "total stroke" of all rods can be made about three inches long. One channel 20-A may contain merchandise items two inches deep, requiring "actual strokes" of about two inches. The respective lugs 34 should then be spaced about two inches apart; the respective guard 37 should be about one inch long and the location of pin 32 can be about one inch in front of the rear-most position for such pins. For a channel 20-B, containing merchandise only one inch long, the length of the guard 37 must be about two inches.

Further mechanical details were found important in connection with this mechanism, particularly when vending unpackaged items of merchandise, the surfaces of which may be irregular in shape, roughness etc. Attention must be drawn mainly to the problem of moving the merchandise smoothly along its channel, and discharging it safely at the end. One desirable means to this end consists in guide frames 38, sometimes called merchandise hoppers, which are properly dimensioned for each type of merchandise and suitably attached to the lugs 22, in front thereof, as best shown in Figures 8 and 11. At the end of each forward stroke of a rod 28, the holding lug of such a guide frame comes to rest adjacent the very front edge of the respective shelf; and the guide frame 38 itself has then been moved forward beyond the front edge of the shelf, allowing the merchandise to drop into the trough 16. In order to allow ready insertion and discharge of merchandise, the guide frames are open on top and bottom. For simplicity of manufacture they may also be open in front, and consist simply in bent strips of thin and light sheet material, suitably secured to the lugs 22 by rivets or the like.

In order to avoid interference with the discharge of superposed merchandise items, the guide frames successively arriving at the front rollers 23 must be swung around such rollers by 180 degrees in order to clear the merchandise discharge space in the front portion of the machine; and this must be done on all actual strokes, including the shortest ones used for the merchandise of minimum depth. This, in turn, requires that the periphery of a front roller 23 should not exceed about twice the minimum stroke length; in other words, that the rollers 23 be rather small and that accordingly the shaft 24 has limited diameter, as mentioned above.

In order to move the unpackaged and other merchandise forward along a magazine channel without jarring, jamming and other trouble, it is further necessary that the guide frames 38 and lugs 22 be prevented from tilting. For this purpose these lugs, as best shown in Fig. 8, have guide and attachment clips 39 extending longitudinally along the conveyor band 21 and suitably secured thereto; these guide and attachment clips being prevented from tilting by the feature that they slide between closely adjacent top and bottom structures 40, 41 of the channels 20. The top structures 40, as best shown in Fig. 6, are provided by the undersides of the edge portions of the shelf sectors or plates 10 and the bottom structures 41 by top surfaces of suitably bent and attached guide plates 42. In the embodiment shown one guide plate 42 is provided for and coextensively with each channel. It provides also retainer gages 43 defined by the stops 23A for the rollers 23, 26. Still further it provides supports

for the actuator rod bearings 29 and further supports for the transverse shafts 24, 25.

I have found it particularly desirable to shape the lugs 22 and their guide and attachment clips 39 in the preferred manner shown in Figs. 8 and 11. Each clip 39 of this form substantially consists in a metal strip at least somewhat wider than the conveyor band 21, and having four definite portions as follows: (1) an upright, normally upstanding portion forming the lug 22 for attachment of the merchandise cage or holder 38; (2) a flat, short, normally more or less horizontal portion 22-A, having a top surface in contact with the undersides 40 of the shelf plates 10A, 10B; (3) another flat, short normally more or less horizontal portion 22B connected to 22A by a vertical component 22C, disposed slightly below 22A, and secured to the band 21, as by rivets 22E; the band 21 being in contact with and supported by the surface 41; and (4) an upright, normally depending portion forming the service lug 34 and connected to the back edge of the portion 22B. The portions 22A, 22B are slightly wider than the band 21. The upstanding lug 22 is preferably disposed centrally of the portion 22A, the depending lug 34 laterally of the portion 22B. It will thus be seen (Fig. 8) that each clip 39 has substantially a zigzag-shaped form, in side view, comprising three vertical components 22, 22C, 34 and two horizontal components 22A, 22B.

I have further found it very desirable to support the underside of the higher portion 22A from the band 21 in order to prevent it safely from distortion; for instance by rivets 22D secured to the band below such platform, and similar to the rivets 22E. This will be understood more clearly when it is considered that the channel 20 desirably has a height at least slightly greater than the thickness of the clip-attaching portion 22B, in order to avoid mechanical binding even in the event that the shelves are slightly bent by the variable load of merchandise thereon, or that some dust or dirt has been deposited in the channels.

It will further be seen that the conveyor band 21 of each row has approximately one-half of its total length (the equivalent of the length of a channel 20) connected with article-holding clips 39. When the machine is newly loaded with merchandise all these clips and their article containers 38 and items of merchandise therein are on top of the shelves. When the machine is empty, all but the last of the clips 39, with empty containers 38, are below the shelves. For reloading with merchandise they are manually retracted; the operating mechanism will not interfere, by virtue of the guards 37 as described.

The vending process consists in moving the operating run of a proper conveyor 21 to the front of the machine, by a proper distance controlled by the guard 37, and simultaneously removing the preceding, empty article holder 38 and lug 22 from the cabinet space in front of the shelves 10 to allow free falling of the newly vended merchandise item; and in suitably controlling these several motions etc. as will be described hereinafter. During the mechanical motion of the conveyor and attached parts, the previous holders 22, 38 are being swung around the front roller 23, in vertical planes, while the new item of merchandise, in the next container 38, is still being supported at least in part by the shelf plates 10A, 10B. As the new item reaches the front position shown in Figure 8, it loses the support of the shelf plates and falls.

I greatly prefer the shelves 10A, etc. to be installed with a pronounced backward slope. This results in a forward slope of the lug 22 and back wall 38A of the article container. Such forward slope, when sufficiently pronounced, causes the items to slide out and consequently to fall in a direction containing a forward component sufficient to counteract interception of falling items by lower shelves 10 and hoppers 38.

It might seem that such a forward slope can be provided also without a backward slope of the shelves; however, closer consideration shows a special advantage of the construction as shown and described. In this connection reference is made to Figure 8, which shows the front item of merchandise in process of falling. It must be kept in mind that in the present machine, the merchandise may have various forms, side and bottom configurations, frictional characteristics, etc. It must further be kept in mind that the shelf plate 10 stops, and practically must stop, somewhere above the front rollers 23; preferably above their front portions. Consideration of Figure 8 will show that due to the backward slope of the tray and forward slope of the lug 22, practically all types of merchandise which can be handled by the conveyor at all will be in sliding contact with and subject to sliding support by the lug 22 and attached container back wall 38A at the precise instant of discharge. If Figure 8 be changed, for instance by making the shelf and conveyor strictly horizontal while leaving other features unchanged, it would be unpredictable whether a given item of merchandise, at said instant, leans against the front of the back wall of the container 38—it being necessary for obvious reasons to allow some little looseness in said container. This indefiniteness of position and support would lead to the possibility, at least for a great many typical forms of items, that wedging instead of free discharge occurs at the critical moment.

In some cases the discharge of articles from the universal merchandise conveyors can be made still safer, and the conveyor construction still simpler, by omitting the holders 38 entirely or partly, while retaining the other features as described, which insure proper display, propelling and discharge. When omitting part of the holders 38, it may still be desirable to retain their side walls 38B. However, it also is possible to hold the articles only by the movable lugs 22 and/or added stationary, lateral, vertical walls 44 extending between the channels (see Figure 13). Lateral tilting of merchandise is then prevented by walls 44 instead of clips 38B.

In order to cause the vending and discharging process described, the purchaser as mentioned operates a handwheel, coin device and push button, before picking up the article from the trough at the bottom of the machine. Details of this handwheel, coin device etc. will now be described.

The handwheel 11 is preferably located at a convenient elevation above the floor, and at one side of the cabinet as shown. It rotates a shaft 45 (Figs. 2, 3), which extends horizontally adjacent to and parallel with a sidewall 46 of the cabinet 18. Within the cabinet, adjacent the back wall 47, a pair of sprockets 48, 49 are mounted on the shaft 45. Each sprocket operates a chain, one chain (50) extending to the top and another (51) extending to the bottom of the cabinet. Each of these chains engages a further sprocket, in the top part (52) and in the bottom part (53) respectively; each of the latter sprockets 52, 53 being interconnected by a horizontal chain 54, 55, with an upper or lower countersprocket 56, 57 adjacent the other sidewall 58. All sprockets may be of the same size, thereby insuring uniform horizontal motions of the upper and lower chains 54, 55.

These chains are vertically interconnected by, and used for the lateral motion of, the motor standard 12, which is supported and guided at least at one end by suitable means such as a small carriage 59. Clockwise rotation of the handwheel moves the motor standard to the left; counterclockwise rotation returns it to the right. The position of the motor standard is clearly indicated to the purchaser by an index finger 60 secured to the top of the standard, reaching over the set of shelves, and depending in front of the machine, as best shown in Fig. 4. This index finger and the standard carrying it will register, at any one operative position thereof, with an en-

fire set of merchandise rows R-1 or R-2 etc.; these rows being accurately superposed above one another for this purpose.

In order to insure positioning of the standard and index in proper operative positions, the shaft 45 carries a mechanical and electrical indexing device 61 (Fig. 14). This device comprises a first cam 62, in form of a notched circular disc. Two notches 63, at 180 degrees from one another, are shown. They can be engaged or disengaged by a locking bar or latch 64, actuated for engagement with the cam by a solenoid 65. The second cam 66 of the indexing device has two low lobes 67 at locations angularly aligned with the notches 63, to operate a cam follower roller 68 for the control of a single throw switch 69. The peripheral spacing between the notches 63 and low lobes 67 coincides with the lateral spacing between channels 20 on the shelves 10, so that the latch 64 and switch 69 can be operated only when the motor standard 12 is in operative position behind such a channel. That such a position has been reached can be noted by observation of the index finger 60 and also by a slight clicking noise which occurs when the roller 68 falls into the low lobe 67. At such points, and only there, the switch 69 closes a slug rejector circuit 70 through a slug rejector 71 having a rejector relay coil 70A or the like, as is well known to the art.

When a coin is then inserted in the slot 13 and allowed to fall through the chute 72 of the slug rejector (see Fig. 2), one or several of the usual double throw coin switches 73, 74, 75 are momentarily deflected from their normal position, shown in Fig. 14, to a position wherein they break the slug rejector circuit and close a momentary stepper circuit for instance circuit 76 or 77, through a solenoid 78, 79 or 80 of a conventional totalizer, 81. These solenoids, when so energized, raise a lever 82, by different numbers of degrees respectively, thereby producing different amounts of rotation of a pawl and ratchet mechanism 83 and of a totalizer contactor 84 coupled therewith. Depending on the total rotation obtained, the contactor stops at some point of the periphery of a stationary disk 85, and establishes contact with one of several contacts 86 thereon. The lever 82 and contactor 84 are then held in each position so established, by a spring-loaded latch 87 engaging a notch 87A, against the pressure of a torsion spring 88 tending to return the contactor to its normal or zero position. As the contactor 84 establishes and holds contact with one of the contacts 86 a starter circuit 89 through a corresponding motor 15A or 15B etc. is prepared. (This preparation may be indicated by the lighting up of a signal lamp 90, corresponding in position with the proper shelf 10A, 10B etc. The lamp circuit is shown at 91.) The deflection of a coin switch, the operation and latching-in of the totalizer mechanism, and the preparation of the corresponding starter circuit follow practically in an instant upon the dropping of the coin.

Thereupon the purchaser can complete the proper starting circuit 89 by pressing a push button 14A adjacent the lighted lamp 90, unless he prefers on final thought to change the plan and produce, by conventional means not shown, a return of his coin and return of the electrical system to its normal and original position. It should be understood that various refinements of this last-mentioned kind are known to the art; also for purposes such as temporary retention of coins, automatic coin changing and the like.

The pressing of the push button 14A temporarily reverses the pertinent double throw switch 92, and thereby completes the starting circuit previously prepared, starting the selected motor 15A, 15B etc. As soon as such a motor starts running, its reducer output shaft 93 begins to rotate a cam and crank unit 94.

This unit (Fig. 10) has a crank pin 95, rotating in the plane of the pertinent shelf 10, which pin now begins to engage a slot 96 extending transversely of the pertinent

channel 20, in a yoke 97. This yoke is guided for reciprocation in a direction parallel with the channel 20, by strips 98 secured to the motor-reducer base. The yoke is adapted to engage the back end of the pusher rod 28, 5 and does so when it has been moved forward by a sufficient distance, depending on the aforementioned adjustment of the actual stroke. Every full revolution of the pin 95 and reciprocation of the yoke 97 may occupy for instance a few seconds; it begins with a forward stroke and ends with the return stroke to the original position. Desirably the forward stroke of the yoke is slightly longer than the total stroke of the pusher rod, in order to insure the absence of jamming on pusher rods utilizing the entire stroke length. In this manner, undue starting loads 10 are avoided.

Each unit 94 also has a cam 99 adapted to control a double-throw snap-action switch 100. In normal position this switch closes the aforementioned starting circuit 89 for the motor 15. Promptly upon the start of rotation 20 of the motor and cam 99, and practically over the entire remaining part of the periphery of this cam, the switch 100 is and remains reversed, to close an operating circuit 101 for the motor 15. From the moment when this circuit 101 has been established the push button 14 can 25 safely be released. Only a split second is required for the change from the starting to the operating circuit, and the normal period of push button depression extends well beyond this interval. Exceptionally, if a push button be merely touched in passing rather than normally depressed, 30 the motor 15 may stop before the switch 100 has been reversed; however, this is readily corrected by pushing the push button again and more properly.

When an entire revolution of the pin 95 has been completed the cam 99 opens the operating circuit 101 by 35 reversing the switch 100 again. At that time no starting circuit remains, regardless of possible intervening operations either intentional or faulty. Even the dropping of additional coins, pushing of push buttons, or attempted turning of the handwheel will not interfere. This is 40 achieved mainly by a double throw switch 102 in a relay 103, energized by a switch 104 in the totalizer. The switch 104 is open when, and only when, the contactor 84 is in its normal zero position. The turning of the contactor to any one contact 86 has closed the switch 45 104, thereby energizing the relay 103, which has reversed the relay switch 102 from its normally closed position 102-A to its normally open position 102-B. In said position 102-B the switch 102 has allowed the establishment 50 of the aforementioned operating circuit 101. It has also established a parallel circuit 101-S, including the aforementioned solenoid 65. This has locked the cam 62 and motor standard 12, insuring undisturbed completion of the vending operation even in the event of accidental interference with the handwheel 11. The opening of switch 55 102 in position 102-A has broken the slug rejector circuit 70, although that circuit remains closed at 69.

Due to the opening of both the starting and operating motor circuits 89, 101, the previously energized motor 15 now stops, at the point where its yoke and push rod have completed a forward and reverse stroke.

Shortly before this time, when the forward stroke was completed, the purchaser could see the selected item of merchandise fall into the trough 16. He should now open the trough to remove the merchandise. Premature opening of the trough and initiation of dependent actions can 60 be avoided by a conventional, automatic locking arrangement (not shown).

By the time the purchaser can have opened the trough pursuant to the fall of the merchandise, the motor cycle is complete. The opening of the trough momentarily 65 closes a normally open switch 105, completing a reset circuit 106 (through the switch 104 which is still closed due to the latching-in of the totalizer) and thereby momentarily energizing a reset or latch-out solenoid 107 in the totalizer. This unlocks the lever 82, pawl and ratchet 70

mechanism 83 and contactor 84 and allows the spring 88 to return the contactor to its normal zero position. This in turn opens the switch 104, terminating the reset circuit even if the trough remains open for some more moments. (This trough can be counterweighted for automatic closing by well-known means not shown.) The opening of the switch 104 also deenergizes the relay 103, thereby reversing the switch 102 to position 102-A (to prepare for or make a new slug rejector circuit 70) and removing it from position 102-B (to make sure that the proper sequence of starting and operating motor circuits ensue again, pursuant to the next coin insertion; and also to unlock the handwheel shaft and motor standard).

It will be seen that the described conveyor mechanism is actuated only pursuant to proper selection by vertical selector means (11, 45, 48, 49 . . . 59, 60) and horizontal selector means (13, 71, 81, 100), by separate actuator means (14) to start the automatic vending operation and (16, 105) to complete it. The inherent sales appeal of the machine is basically insured by the possibility of making said proper and definite selection, involving the actual item of merchandise to be delivered, and of manually actuating the vending operation when the definite selection has been made; not before.

This sales appeal is further enhanced by the foolproof operation of the machine; mainly by the feature that the transaction, once definitely started, is undisturbedly completed even in case of attempted interference. The locking features (61, 103) are particularly useful in this connection.

A number of modifications will occur to persons skilled in this art upon a study of this disclosure. Underlying features of the invention are claimed to the extent defined as follows.

I claim:

1. A vending machine for miscellaneous articles, comprising a set of spaced superposed shelves; a plurality of spaced, juxtaposed channels in each shelf; conveyors in such channels; a plurality of article holders spaced along and secured to each of said conveyors, such holders extending from the upper run of the conveyor upwardly through and from the respective channel, spacing the articles which rest and slide on the respective shelf, by at least one half the front roller circumference of each conveyor and holding such articles against tilting; an actuator lug secured to each article holder, extending downwardly through and from the respective channel; an actuator rod extending adjacent to and parallel with each of said conveyors, adapted to be reciprocated along the conveyor over predetermined distances greater than said respective spacing of articles, and adapted when moved in one direction to contact an actuator lug and to impel it and the parts secured thereto by a distance substantially equal said respective spacing; and motor control means so to reciprocate a selected actuator rod and thereby to discharge a selected, displayed article from its channel.

2. A vending machine as described in claim 1, wherein each article holder and actuator lug is formed by a one-piece clip having a portion extending along the conveyor.

3. A vending machine as described in claim 2, wherein each article holder has attached thereto, beyond the channel, an article container open at the top and bottom.

4. A vending machine as described in claim 3, wherein each article container is at least partly open in front.

5. A vending machine as described in claim 1, additionally comprising stationary partition walls extending upwards from and secured to the shelves, to prevent articles from falling or tipping laterally.

6. A vending machine for miscellaneous articles, comprising a set of spaced superposed shelves; a vertical window spaced from and substantially coextensive with the set of shelves; article receiver means below the space between the window and the set of shelves; a plurality of spaced, juxtaposed channels in each shelf; conveyors in

such channels; a plurality of article holders spaced along and secured to each of said conveyors, such holders extending from the upper run of the conveyor upwardly through and from the respective channel, displaying at least front portions of the foremost article on each conveyor, behind said window, and holding the articles which rest and slide on the shelves, spaced by at least one half the front roller circumference of each conveyor; an actuator lug secured to each article holder, extending downwardly through and from the respective channel; an actuator rod extending adjacent to and parallel with each of said conveyors, adapted to be reciprocated along the conveyor over predetermined distances greater than said respective spacing of articles, and adapted when moved toward the window to contact an actuator lug and to impel it and the parts secured thereto by a distance substantially equal said respective spacing; and motor control means so to reciprocate a selected actuator rod and thereby to discharge a selected, displayed article into the article receiver means.

7. A vending machine according to claim 6, wherein the motor control means comprises coin receiver means, shelf selector means, channel selector means, and electric interlock means so arranged that vending of any articles requires removal of any previously vended article from the article receiver means and subsequent operation of the coin receiver and selector means.

8. A vending machine according to claim 7, comprising means to lock the selector means upon insertion of a coin in the coin receiver means, and means to unlock the selector means upon removal of a vended article from the article receiver means.

9. A vending machine for miscellaneous articles, comprising a cabinet; a window in the front of and coextensive with a major part of the front of the cabinet; a set of spaced superposed shelves sloping slightly in the direction away from the window, the set being substantially coextensive with the window; article receiver means below the space between the window and the set of shelves; a plurality of spaced, juxtaposed channels extending in and parallel with each shelf toward the window; conveyors extending in and parallel with such channels; a plurality of article holders spaced along and secured to each of said conveyors, such holders extending from the upper run of the conveyor upwardly through and from the respective channel, displaying at least front portions of the foremost and uppermost article on each conveyor, behind said window, and holding the articles which rest and slide on the shelves, spaced by at least one half front roller circumference of each conveyor; an actuator lug secured to each article holder, extending downwardly through and from the respective channel; an actuator rod extending adjacent to and parallel with each of said conveyors, adapted to be reciprocated along the conveyor over predetermined distances greater than said respective spacing of articles, and adapted when moved toward the window to contact an actuator lug and to impel it and the parts secured thereto along and parallel with the shelf, by distances substantially equal said respective spacing; and motor control means so to reciprocate a selected actuator rod and thereby to downwardly and slightly forwardly discharge a selected displayed article, for interception in the receiver means.

10. A vending machine according to claim 9, wherein each shelf comprises a series of separate plates and means, comprising shafts for the conveyor rollers, to hold such plates together as a shelf.

11. A vending machine according to claim 10, additionally comprising an elongated, rigid channel element extending along each channel and secured to the shelf at and below each channel; the shafts being held by said channel elements.

12. A vending machine according to claim 11, additionally comprising slide bearing means for the actuator rods, spaced along and secured to said channel elements.

13. A vending machine for miscellaneous articles, com-

prising a set of spaced superposed shelves; a plurality of spaced, juxtaposed channels in each shelf; conveyors in such channels; a plurality of article holders spaced along and secured to each of said conveyors, such holders extending from the upper run of the conveyor upwardly through and from the respective channel; an actuator lug secured to each article holder, extending downwardly through and from the respective channel; an actuator rod extending adjacent to and parallel with each of said conveyors, adapted to be reciprocated along the conveyor over predetermined distances greater than said respective spacing of articles, and adapted when moved in one direction to contact an actuator lug and to impel it and the parts secured thereto by a distance substantially equal said respective spacing; a standard substantially as high as said set of shelves and adapted to be reciprocated therewith; motor means mounted on said standard and adapted to reciprocate actuator rods of a selected shelf; means to move the standard to selected channels; and means to control the motor means and thereby to reciprocate a selected actuator rod to discharge a selected article from its channel.

14. A vending machine according to claim 13, wherein

the motor means comprises at least one motorized reducer; a disc on the output shaft of the reducer; a cam surface peripherally formed on the disc; a cam switch associated with the cam surface and forming part of the means to control the motor means; a pin extending from the disc in a direction parallel with the output shaft; and a yoke adapted to reciprocate transversely of said direction, having an elongated, transverse slot associated with the pin, and being adapted to reciprocate actuator rods.

15. A vending machine according to claim 13, wherein the motor means comprises one of said motorized reducers, discs, cam switches and yokes for each shelf; such reducers being mounted on a vertical standard, and the standard being adapted to be reciprocated behind and along the set of shelves.
